CLAIM

The ornamental design for a label, as shown and described.

DESCRIPTION

The patent or application file contains a least one drawing executed in color. Copies of this patent or patent application publication with color drawings will be provided by the Office upon request and payment of the necessary fee.

FIG. 1 is a front view of the first embodiment of a label, showing our new design.

FIG. 2 is a front view of the second embodiment of a label, showing our new design.

FIG. 3 is a front view of a third embodiment of a label, showing our new design.

FIG. 4 is a front view of a fourth embodiment of a label, showing our new design.

FIG. 5 is a front view of a fifth embodiment of a label, showing our new design.

FIG. 6 is a front view of a sixth embodiment of a label, showing our new design.

FIG. 7 is a front view of a seventh embodiment of a label, showing our new design.

FIG. 8 is a front view of an eight embodiment of a label, showing our new design.

FIG. 9 is a front view of a ninth embodiment of a label, showing our new design; and,

FIG. 10 is a front view of a tenth embodiment of a label, showing our new design.

The broken lines showing wording, symbols, barcodes, trademarks, and boxes are environment only and form no part of the claimed design.

1 Claim, 10 Drawing Sheets
(10 of 10 Drawing Sheet(s) Filed in Color)
